UNITED STATES PATENT OFFICE.

NATHANIEL FROST, OF BLOOMINGTON, ILLINOIS, ASSIGNOR TO AMERICAN FOUNDRY & FURNACE CO., OF BLOOMINGTON, ILLINOIS.

WARM-AIR FURNACE.

1,201,033.

Specification of Letters Patent.

Patented Oct. 10, 1916.

Application filed April 23, 1915. Serial No. 23,366.

To all whom it may concern:

Be it known that I, NATHANIEL FROST, a citizen of the United States, and a resident of Bloomington, in the county of McLean 5 and State of Illinois, have invented a new and Improved Warm-Air Furnace, of which the following is a full, clear, and exact description.

The invention relates to furnaces such as 10 shown and described in the Letters Patent of the United States, Nos. 862,067 and 1,018,967, granted to me on July 30, 1907, and February 27, 1912, respectively.

The object of the present invention is to 15 provide a new and improved warm air furnace more especially designed for use in churches, schools and other large buildings and arranged to provide large heating surfaces for the air to pass over with a view 20 to increase the efficiency of the furnace, to relieve the parts of undue strain and to prevent unequal expansion and contraction in the fire box.

In order to produce the desired result, use 25 is made of a furnace proper having a top provided with a smoke outlet adjacent the rear end, a radiator mounted on the said top of the furnace and spaced from the same, the said radiator having upright air 30 passages for the air to pass through after the same has passed up the sides and over the top of the furnace, the said radiator also having longitudinal smoke passages into which leads said smoke outlet to cause the 35 smoke and gases from the burning fuel in the furnace to pass through the radiator and thus heat the air passages and the air passing through the same.

A practical embodiment of the invention 40 is represented in the accompanying drawings forming a part of this specification, in which similar characters of reference indicate corresponding parts in all the views.

Figure 1 is a longitudinal central section 45 of the warm air furnace; Fig. 2 is a cross section of the same on the line 2—2 of Fig. 1; Fig. 3 is a sectional plan view of the same on the line 3—3 of Fig. 1; Fig. 4 is a front elevation of a portion of the furnace; and Fig. 5 is a sectional plan view of 50 one of the sides of the fire box, the section being on the line 5—5 of Fig. 1.

In heating and ventilating churches, 55 schools and other large buildings, it is the practice to employ one or more furnaces or

air heaters set up within a casing or brick-work connected by air ducts with a fan or blower employed for forcing fresh air over the heaters to raise the temperature of the air which latter is then conducted by air 60 flues to the various rooms to be heated. The warm air in entering a room forces the cold and foul air out through suitable vent registers thus insuring proper heating and 65 ventilating of the room, and sometimes exhaust fans are employed to facilitate the heating and ventilation.

Within the brickwork or casing A is arranged a furnace proper having a fire box B provided with a grate C, and an ash pit 70 D. In the construction of the parts mentioned, use is made of a base E containing the ash pit D and supporting the grate C. The upper ends of the sides of the base E support the lower ends of the sides G of 75 the fire box B, and each of the said sides G is made in sections joined and fastened together at the adjacent side edges by outwardly extending vertical flanges G' and bolts G² or other fastening devices, as fully 80 shown in Fig. 5. Each of the sections of a side G is corrugated with the corrugations extending vertically, and the outer faces of the side sections are provided with vertically disposed integral radiating flanges G³. The 85 top or roof I of the fire box B is made in sections corresponding to the sections of a side G, and each top section is of arch shape and corrugated so as to present a greater 90 surface against which the air is forced, and the said sections are joined and fastened together at their adjacent side edges by transverse flanges I' and bolts I². Each top section is also provided with upwardly extending integral radiating flanges I³, which also 95 add to the heating area. The sides of each top section are provided with horizontal flanges I⁴ resting on and fastened to corresponding flanges G⁴ on the upper ends of the side sections. By the arrangement described a large heating surface is provided 100 at the sides G and top I, and the said sides and top are reinforced and by corrugating the sides G and top I provision is made for expansion and contraction thereof to prevent undue straining and cracking of the furnace. The front sections of the sides G and top I are fastened to the front B' of the fire box B and which front B' is attached to the inner surface of the furnace 105

front E^2 . The rear sections of the sides G and top I are attached to a box-like breeching J .

In order to protect the sides of the base E from the heat of the burning fuel on the grate C , use is made of side linings F in the form of upwardly and outwardly curved plates, as plainly shown in Fig. 2. The side linings F are spaced from the sides of the base E and fit with their upper ends on the lower portions of the corrugated sides G , and the said linings F form air spaces with the base sides. Air vents E' are arranged on the front E^2 of the furnace and lead to the said air spaces to allow cool air to pass into the said air spaces for keeping the upper portions of the sides of the base F comparatively cool. The front E^2 is also provided with doors E^3, E^4 leading to the fire box B and the ash pit D , respectively. The sides G of the fire box B are spaced from the inner faces of the sides of the casing A to provide passages for the air passing into the casing A through suitable ducts H opening into the casing A opposite the ash pit D , as plainly indicated in Fig. 2. A blower (not shown) is connected with the air ducts H to force the air through the said ducts into the casing A and against the side walls of the ash pit D and the fire box B to pass upward over the arched top I to be heated by contact with the said surfaces.

Above the fire box B is arranged a radiator K supported at its rear end on the top 35 of the breeching J and fastened at its forward end on the front E^2 and practically filling the transverse space between the side walls of the brick casing A . The radiator K is preferably in the form of a rectangular 40 box, the under side of which is spaced from the top I of the fire box B , as plainly shown in Figs. 1 and 2, so that air passing up on each side of the firebox may pass freely over the entire top thereof and thus insure more 45 complete heating of such air. The radiator K while practically filling the space laterally between the brick walls A and thus preventing any appreciable amount of air 50 passing upward at the sides is provided with vertically disposed air passages L for the passage of the air passing up the sides G and over the top I of the furnace, the radiator projecting laterally beyond the 55 sides of the furnace and substantially filling from side to side the space above the same and causing the air arising along the sides of the furnace to be deflected inwardly and hug and pass entirely over the top of the 60 furnace and then pass through the radiator, as any escape of air at the sides to the plenum hereinafter referred to will be effectually prevented. The radiator K is further provided with forwardly extending smoke 65 passages N connected at their rear ends with a smoke outlet O arranged in the top of the

breeching J . The forward ends of the smoke passages N lead to a chamber P in the forward end of the radiator K and from this chamber P extend return smoke passages Q connected at their rear ends by branch passages R with a chimney flue S leading to the chimney. Thus the smoke and gases from the fire box B pass rearwardly and up through the outlet O into the radiator K to travel forwardly and 70 around the smoke passages N into the chamber P from which the smoke and gases pass rearwardly through the passages Q to be conducted by the branch passages R into the chimney flue S to finally reach the chimney. It will be noticed that by this arrangement the smoke and gases passing through the passages N and Q heat the air passages L and consequently the air passing through the same. By reference to Figs. 1 and 2, 85 it will be noticed that the top of the radiator is a distance from the top of the casing A to form with the latter a plenum chamber T from which lead flues U to the different rooms to be heated. 90

The rear end of the radiator K adjacent to the smoke outlet O is connected by an opening N' with the branch passages R and is controlled by a damper V which is normally closed but when opened provides 95 a direct passage for the smoke and gases to pass from the outlet O by way of the opening N' and branch passages R into the chimney flue S without first passing through the smoke passages N, Q and R , as previously explained. The damper V is opened whenever it is desired to produce a strong, direct draft in the fire box B and also to reduce the heat of the air. The damper V is provided with a transversely extending shaft V' journaled in suitable bearings held on the rear end of the radiator K , and one end of the shaft V' extends through a side wall of the radiator K to the outside thereof. On the outer end of the shaft V' is secured an arm V^3 pivotally connected with a damper rod V^4 extending forwardly through the front E^2 of the furnace to be within convenient reach of the furnace attendant to enable the latter to open and close 110 the damper V whenever it is desired to do so for the purpose above mentioned. 115

It will be noted that the damper V is pivoted at its lower end along a straight line the upper portion being rounded and that when swung forwardly to close opening N' that it rests against the rear wall of the radiator. It is also to be noted when said damper is lowered to permit the rapid exit of the products of combustion and to produce a quick-draft, that it lies flat within the chimney flue S and that in this position it will not be affected to any appreciable extent by heat, and thus burning out of and warping prevented. 120 125 130

A cleaning door E⁵ is arranged in the front E² opposite the chamber P and the smoke passages N for conveniently cleaning the same whenever it is deemed necessary

5 to do so.

The radiator is to fill practically the entire space between the side walls of the casing only sufficient clearance being used to allow for expansion which will be slight.

10 Having thus described my invention, I claim as new and desire to secure by Letters Patent:

1. A warm air furnace and heater consisting of a combustion chamber having an arched top and a breeching at its rear end, said breeching having a smoke outlet, an elongated radiator supported at its rear end on said breeching and having communication through the same with the smoke outlet of the combustion chamber, said radiator spaced from the combustion chamber and projecting beyond the same at the sides, a series of transverse rows of vertical air passages extending through the radiator, a smoke chamber at the front and rear of the radiator, a centrally disposed forwardly extending smoke passage and side return smoke passages connecting the front and rear smoke chambers of the radiator, a smoke outlet at the rear end of the radiator, communicating with a smoke flue, and a damper controlling the connection of smoke outlet of the radiator and smoke flue whereby the products of combustion may be discharged directly from the combustion chamber through the smoke flue, or caused to circulate forwardly and rearwardly through the radiator.

2. A warm air furnace comprising a combustion chamber having an arched top provided with a smoke outlet at its rear end, an elongated radiator supported slightly above said chamber and communicating at its rear end with the smoke outlet of the combustion chamber, said radiator spaced vertically from the combustion chamber and projecting beyond the same at the sides, said radiator also having a smoke outlet at its rear end, and having front and rear smoke chambers and forwardly and rearwardly extending smoke passages connecting the smoke chambers, a series of transverse rows of vertical air passages interposed in said forwardly and rearwardly extending smoke passages, a smoke flue connecting with the smoke outlet at the rear of the radiator, and a damper controlling communication between said smoke outlet and smoke flue whereby direct draft through the smoke flue may be secured and temperature reduced through the radiator.

3. A warm air furnace structure comprising a casing having air ducts leading into the lower portion thereof and a plenum chamber in its upper portion provided with air ducts for distributing heated air, a combustion chamber set in said casing, an arched top for said combustion chamber, the combustion chamber having corrugated sides and a rear breeching provided at its top with a smoke outlet, a radiator mounted on said breeching and coextensive longitudinally with the combustion chamber and breeching and having its underside spaced therefrom, said radiator substantially filling from side wall to side wall of the casing the space above the combustion chamber whereby air ascending along the sides of the combustion chamber will be deflected and caused to hug the arched top before passing through the radiator, said radiator having a series of rows of transversely spaced-apart vertical air passages opening into the said plenum chamber, the radiator further having a horizontal smoke circulating passage connected at its outlet end to the breeching outlet, said air passages extending through the smoke circulating passages, and a chimney flue connected with the discharge end of the smoke circulating passage.

4. In a warm air furnace structure the combination with a casing having cold air ducts leading into its lower portion and a plenum chamber in its upper portion provided with ducts for distributing heated air, a cast metal combustion chamber having an arched top, an overhead radiator connected at its rear end to the rear end of the combustion chamber and spaced therefrom, said radiator and combustion chamber being of general oblong form, the radiator provided with forward and return smoke passages and a series of transverse rows of vertical air tubes passing through said smoke passages, said radiator substantially filling from side to side, the space above said combustion chamber, whereby heated air ascending along the sides of the combustion chamber will be deflected and caused to hug the arched top and then pass through the radiator into the plenum chamber, and a smoke outlet flue and a damper controlling communication between the combustion chamber, the smoke passages and the smoke outlet flue.

In testimony whereof I have signed my name to this specification in the presence of two subscribing witnesses.
